HOLDER FOR CIGARETTE PACKAGES

Joseph P. McEnery, New York, N. Y.

Application February 26, 1937, Serial No. 127,813

9 Claims.

(Cl. 206—41)

This invention relates to holders for cigarette packages.

An object of this invention is a cigarette package holder which will effectively prevent crushing of a partially emptied cigarette package and is of such construction that it may be collapsed into a small compass or may be arranged in the form of a bracelet or the like.

Other objects, novel features and advantages of this invention will become apparent from the following specification and accompanying drawing, wherein:

Fig. 1 is a perspective view of a cigarette package equipped with a holder embodying the invention;

Fig. 2 is a vertical section on an enlarged scale;

Fig. 3 is a fragmentary top view;

Figs. 4 and 5 are fragmentary side elevations;

Fig. 6 is a bottom view;

Fig. 7 is a section on the line 7—7 of Fig. 6;

Fig. 8 is a view similar to Fig. 6 of a modification; and

Fig. 9 is a plan view of the holder, laid out flat.

In Fig. 1, 10 represents a standard cigarette package having the usual inner tin foil wrapper 11 and the outer paper wrapper 12 which does not cover the top of the package but does have flaps 13 (see Fig. 6) extending from the bottoms of its side edges and being folded inwardly.

30 The holder comprises a rectangular wire frame 14 adapted to overlie the top of the cigarette package. The frame supports a cover 15 having a plurality of tongues 16 wrapped around one side of the frame 14 to hinge the cover 15 thereon.

35 A spring 17 has two coil portions surrounding said frame side and a portion bearing against the cover 15 tending to swing the same into the position shown in Fig. 1. A side strip 18 is hinged to each end of the frame 14 by looping the strip around the frame. A wing 19 is formed

40 from an extension of the strip 18 beyond the hinged loop and is of substantially the same width as the cigarette package. A loop 20 is hinged to the bottom of each side strip 18 by bending the end of the strip around the loop. The two loop members 20 are adapted to extend between the bottom of the package and the flaps 13 into the interlocking relation shown in Figs. 6 and 7; one loop member 20 being provided with a shoulder 21

45 for locking engagement with the other loop member as shown in Fig. 7. The front edge 22 of the upper hinged portion of each side strip 18 is outwardly flared. Each end of the cover is cut out at 23 to receive such hinged portion and permit

50 swinging of each side strip 18 into a position approximately 180° from the position shown in Fig. 1. The forward wall of each cut-out portion is provided with an ear 24 which is adapted for engagement under the flared edge 22 to lock the

55 cover in closed position.

In the use of the holder, the tin foil is removed from the top of a cigarette package and the wings 19 are inserted between the inner and outer wrappers. The loops 20 are then passed between the bottom of the package and the flaps 13 into the relationship shown in Fig. 6, thereby locking the holder around the package. During the application of the holder to the package, the cover 15 is in closed position as shown in Fig. 4. When it is desired to obtain access to the cigarettes, the frame 14 is slid forward through the upper hinges of the side bars 18 sufficiently to disengage the ears from the flange portions 22 thereby permitting the spring 17 to lift the cover. The cover after being closed is locked by reversing the portion just described.

In the modification disclosed in Fig. 8, the loops 13 are replaced by a single loop 13a hinged to the bottom of one of the side strips 18 which extends the full width of the cigarette package. The loop 13a is provided with inturned ends 13b which extend into the hinged member at the bottom of the other side strip 18. This modification is applied to the cigarette package as above described except that the ends 13b of the loop 13a are assembled with the side strip 18 by spreading them apart and then inserting them in the hinged portion.

The holder above described may be folded into a compact arrangement by reason of the various hinged connections. It may be arranged as a long flat member (Fig. 9) or the various portions may be folded on themselves so that the overall length is merely that of the frame 14. Also, the holder when not in use with a cigarette package 35 may be formed into a bracelet-like loop or arranged in a closure of different forms as may be desired. The various parts of the holder may be formed of any suitable material but preferably 40 are composed of a metal which may be given a highly polished surface.

I claim:

1. A cigarette package holder comprising a top frame, side members hinged to the ends of said frame and having wings for insertion between the inner and outer wrappers of the cigarette package, and means adapted to extend between the bottom of the cigarette package and folded flaps extending from the bottom edges of the outer wrapper for joining together the ends of said side members.

2. A cigarette package holder comprising a top frame, side members hinged to the ends of said frame and having wings for insertion between the inner and outer wrappers of the cigarette package, and a loop hinged to the bottom of each side member, said loops being adapted to extend between the bottom of the package and folded flaps extending from the bottom edges of the

outer wrapper and being provided with interlocking means.

3. A cigarette package holder comprising a top frame, side members hinged to the ends of said frame and having wings for insertion between the inner and outer wrappers of the cigarette package, a loop hinged to one of said side members and being adapted to extend between the bottom of the package and folded flaps extending from the bottom edges of the outer wrapper, and means for connecting said loop to the bottom of the other side member.

4. A cigarette package holder comprising a top frame, a cover hinged to one side thereof, side strips slidably connected to the frame ends and means on said strips and cover engageable by relative movement to lock the cover to the frame.

5. In a cigarette package holder comprising a top frame, a cover hinged to one side thereof and having cutout portions in its ends, side strips slidably connected to the frame ends and having flared portions extending into said cut-out portion, and ears on said cover engageable by relative movement of the frame and strips with said flared portions to lock the cover to the frame.

6. A cigarette package holder comprising a top frame, side members connected to the ends of the frame and having wings for insertion between the inner and outer wrappers of the cigarette

package, and extensions from the bottom ends of said side members for engaging the bottom of the package to secure the cigarette package in the holder.

7. A cigarette package holder comprising a top frame, side members connected to the ends of the frame and having wings for insertion between the inner and outer wrappers of the cigarette package, extensions from the bottom ends of said side members, and means for interlocking said extensions for securing the cigarette package in said holder.

8. A cigarette package holder comprising a top frame, side members hinged to the end of said frame and having wings for insertion between the inner and outer wrappers of the cigarette package, and means hinged to the bottom ends of said side members and extending across the bottom of the cigarette package for securing the package in said holder.

9. A cigarette package holder comprising a top frame, side members hinged to the end of said frame and having wings for insertion between the inner and outer wrappers of the cigarette package, and means connecting the bottom ends of said side members, said means extending across the bottom of the package and securing the same in said holder.

JOSEPH P. McENERY.
